UNITED STATES PATENT OFFICE.

FRED C. AREY, OF OAK PARK, ILLINOIS, ASSIGNOR TO EDGAR AMES TURNER, OF CHICAGO, ILLINOIS.

MACHINE FOR EXPANDING METAL LATHS.

1,318,951.

Specification of Letters Patent. Patented Oct. 14, 1919.

Application filed May 14, 1915. Serial No. 28,015.

To all whom it may concern:

Be it known that I, FRED C. AREY, a citizen of the United States, residing at Oak Park, county of Cook, State of Illinois, have 5 invented a certain new and useful Improvement in Machines for Expanding Metal Laths, and declare the following to be a full, clear, and exact description of the same, such as will enable others skilled in 10 the art to which it pertains to make and use the same, reference being had to the accompanying drawings, which form a part of this specification.

The present invention relates to metal 15 working machinery, and particularly to a machine for expanding a previously slitted sheet to transform it into what is known as expanded metal, and has for its object to produce a simple and efficient machine 20 for expanding a strip or sheet the entire area of which has not been slitted but which contains unslitted areas.

Viewed in another of its aspects my invention may be said to have for its object 25 to produce a simple and novel machine for transforming a flat strip of metal having a central slitted panel into a channel shaped lath unit having the body portion formed out of open mesh and the flanges or sides 30 of unslitted metal whereby, when a plurality of similar units are laid side by side with their flanges touching, a sheet of metal expanded throughout and provided with unexpanded stiffening ribs is obtained.

In carrying out my invention the strip 35 is expanded by applying pulling forces at opposite edges, acting in the plane of the portion to be expanded and, since the strands in the expanded metal are bent out 40 of this plane or rather are bent so as to lie at an angle to this plane and it is desirable that all of the strands be inclined in the same general direction, my invention may be said to have for one of its objects to produce a simple and novel device for insuring 45 that the strands will always be inclined in the proper direction.

The various features of novelty whereby 50 my invention is characterized will hereinafter be pointed out with particularity in the claims; but, for a full understanding of my invention and of its objects and advantages, reference may be had to the following detailed description taken in connection 55 with the accompanying drawings, wherein:

Figure 1 is a top plan view of that portion of a complete metal lath-forming machine arranged in accordance with the present invention;

Fig. 2 is a section on an enlarged scale taken approximately on line 2—2 of Fig. 1;

Fig. 3 is a section on a still larger scale taken approximately on line 3—3 of Fig. 1;

Fig. 4 is a section taken approximately on line 4—4 of Fig. 1;

Fig. 5 is a section taken at right angles to the plane of Fig. 4 just above the bed through the shafts of two of the flanging rolls by which the flanges of the expanded channels are in turn flanged;

Fig. 6 is a section on an enlarged scale approximately on line 6—6 of Fig. 4, only a fragment of the framework being illustrated;

Fig. 7 is a top plan view on an enlarged scale of that portion of the machine in which the expanding of the strips takes place, a strip being shown in position;

Fig. 8 is a section taken approximately on line 8—8 of Fig. 7;

Fig. 9 is a section taken approximately on line 9—9 of Fig. 7;

Fig. 10 is a section taken approximately on line 10—10 of Fig. 7, a strip being omitted.

My invention is particularly adapted for forming channel shaped expanded metal lath units from comparatively narrow strips each having a slitted panel extending down the center, such as are formed in my machine for slitting sheet metal strips disclosed and claimed in my prior application 21,198; and, for the sake of brevity, I shall confine the detailed description to this particular form of machine and product although it will of course be understood that my invention is not limited to this one field. The mechanisms of which the machine is constituted may be divided into four groups, the first of which bends the flat strip into a channel member wherein the unslitted portion is confined between the sides or flanges; second, mechanism for expanding the channels so as to make them wider and at the same time transform the slitted portions into an open mesh; third, mechanism for flanging the sides or flanges of the channels; and fourth, mechanism for straightening the sides of the channels.

The first of these groups of mechanisms

is shown as comprising four sets of complementary rolls, 1, 2, 3 and 4, mounted on a suitable stationary part, 5, which forms the base for the whole machine, and driven in any suitable way from a main driving shaft, 6; the rolls 1 being simply plain feed rolls while one member of each of the sets 2, 3 and 4 is spool shaped, the angle between the inner sides of the flanges and the body portion of the spools decreasing throughout the series until this angle is ninety degrees in the spool shaped member of the rolls 4. The result is that when a strip is fed through the series of rolls, it is bent into the form of a channel whose sides are at right angles with the connecting member. The parts are of course so proportioned that the width of the channel-shaped member into which the strip is formed is just equal to the width of the slotted panel extending down through the center; the work having in cross section the appearance shown in Figs. 7 and 8 just after it passes through the last set of rolls, the sides, 7, being formed of unslotted metal while the connecting piece, 8, is slotted throughout its entire area.

As the work leaves the rolls it passes forward in an inverted position, with the free edges of its flanges lying a short distance above a horizontal bed, 9. On this bed, just in the rear of the rolls 4, are three guiding members including a central block, 10, and side blocks or members, 11 and 12. The height of the blocks or guides is somewhat greater than the width of the flanges of the work. The member 10, at the end nearest the rolls is just wide enough to fit between the flanges of the work, the extreme end being of course tapered to permit it readily to enter the work. The blocks 11 and 12 are spaced apart from the block 10 a distance equal to the thickness of the metal of which the work is made. The block 10 increases gradually in width, the increase being, however, wholly on one side; the members 11 and 12 being of course shaped so as to maintain at all points the passages for receiving the flanges of the work. The result is that as the work is fed forward it is slipped over and rests upon the central guide block and, since the block gradually becomes wider than the width of the unexpanded channel, the latter is caused to expand, transforming the horizontal slotted portion into an open mesh as indicated at 13 in Fig. 7. In expanding, the natural tendency is for the flanges of the expanded portion to place themselves at an angle to the flanges of the unexpanded portion and the straight side of the central block is therefore curved inwardly at the wider end so as to permit the adjacent flange to leave tangentially and avoid producing a sharp corner. This may be explained in another way.

When a sheet, slotted along slightly diag-

onal lines, as shown in Fig. 7, is expanded, there occurs a relative longitudinal movement between the opposite long edges that is, between the downturned flanges in the present instance. After the expansion has been completed, the two edges continue through the machine in the same direction and at the same speed. By causing the gradually-widening expanding block to curve or bend laterally as a whole, the proper ratio is maintained between the distances through which the two flanged edges of the work must travel during the expanding operation; so that one flanged edge simply travels faster than the other while moving along the block. Then, when the expansion is complete and the two flanged edges are required to travel along at the same speed, they leave the expanding block in a tangential direction to each of the curved sides and therefore are permitted to follow a natural course without being forced or distorted.

In order to hold the work upon the guides and keep it from lifting up, I have placed on top of the members 11 and 12 two ledges, 14 and 15, which overhang the central block and engage with the upper surface of the work.

With the construction heretofore described, the strands of the expanded metal lie at an angle to the normal plane of the sheet out of which they are formed and, in order to produce a commercial product it is necessary that this inclination be in the same direction throughout the length of the strip. However, since the expanding forces are mere pulls in opposite directions in the plane of the slotted portion of the work, it sometimes happens that the strands will be inclined in one direction in one portion of the strip and in the reverse direction in another portion. In order to prevent this reversal of the strands, I have provided means for positively controlling the direction in which the strands are inclined, insuring that all of the strands will be inclined in the same direction throughout an entire strip or series of strips. The means for controlling the direction of inclination of the strands is based on the theory that the direction of inclination depends upon the angle which the expanding forces make with the normal plane of the slotted sheet. Where these forces are in the plane of the sheet it is just a matter of chance as to which direction the strands will take; but, by causing these forces to be applied at a definite angle to this plane, the direction of inclination of the strands will be positively determined. Since the actual direction of the expanding forces is at right angles to the flanges of the work, I obtain the angle between these forces and the plane of the slotted strip by displacing the strip itself so as to make an angle

with its normal plane. This can conveniently be accomplished by hollowing out the top of the central block 10 and placing above the recess thus formed a shoe which 5 will press the slitted material downwardly before the actual expansion begins. In the arrangement shown, the top of the block 10 is cut away at the top except that ledges, 16, 17, are left for the purpose of leaving the 10 block at its full height at the sides; these ledges being preferably shaped so as to be very narrow at the top. Lying above the member 10 in proximity to the straight side thereof is a stationary shoe, 18, approximately triangular in cross section, one of the sides being the horizontal upper side, another of the sides being a vertical side extending down into the recessed top of the block to a point which leaves just sufficient 15 clearance between the shoe and the ledge 17 to permit the slitted metal to pass between them, while the third side is one which is inclined upwardly from the vicinity of the ledge 17 until its opposite edge is above the 20 normal plane of the slitted strip. The front end of the shoe 18 is cam shaped as indicated at 19, the shape being such that the extreme front end of the shoe is higher than the plane of the slitted portion of the channel 25 as it enters the expanding mechanism, thus permitting the work to pass readily beneath the shoe so that the slitted portion will be gradually bent downwardly from both edges until, when the actual process of expansion 30 due to the widening of the block 10 begins, there has been a partial expansion due to the pressing of the slitted member 8 from the condition illustrated in Fig. 8 to that 35 illustrated in Fig. 9. With the work in 40 the condition illustrated in Fig. 9, the expanding forces resulting from the pressing apart of the flanges of the work as they pass upon the wider portions of the block 10 are at definite angles to the planes 45 of the deflected slitted material and consequently the inclination of the strands is positively determined.

The placing of the shoe in the manner illustrated secures an additional result. It 50 is evident that the series of strands next to one flange or the other must have a twist in it if the other be straight, that is if the strands of one of these series take the same form or shape as the strands through the 55 body portion of the expanded metal, the strands of the other series must be twisted. By placing the shoe close to one of the ledges and making the upper edge of this ledge narrow and practically sharp, a sharp bend 60 is produced just at the juncture between the slitted portion and one of the unslitted flanges, and the parts which constitute strands when they are separated from each other are bent in such a way that they 65 contain the twist necessary to make them fit

into the structural scheme without bending the upper edge of the metal forming the unslitted flange. The result is that after the expansion is completed, each flange shows in 70 plan a clean edge.

Just beyond the expanding mechanism are two sets of rotary feeding heads, 20 and 21, revolving about vertical axes just above the work-receiving bed, each set being in position to grasp one of the flanges of the work 75 as it leaves the expanding mechanism.

It sometimes happens that the metal does not receive a sufficient "set" in passing through the expanding mechanism, so that after it is finished the work is narrower than 80 was intended. In order to compensate for variation in the character of material I have provided a shoe, 22, containing a slot, 23, in position to receive one of the flanges of the work as it leaves the feeding heads 20. The 85 member 22 is provided with suitable adjusting means, 24, which, in the arrangement shown, consists of a bolt passing through a stationary part and nuts on the bolt to lock the shoe in any adjusted position. If it is 90 found that the work has a tendency to contract in the transverse direction, the shoe 22 is simply adjusted outwardly a slight distance so that it will exert an outward pull 95 on the flange passing through the same and stretch the work transversely to a desired width.

After leaving the expanding mechanism, including the shoe 22, the flanges of the work pass between two sets of rotary flanging heads, 25 and 26, which simply act to bend the lower edges of the flanges of the work inwardly parallel with the plane of the expanded portion. With this arrangement, when two completed lath units are laid side 100 by side the two contacting flanges form a T-beam. The construction of these flanging heads is clearly shown in Fig. 2. Each set consists of two rotary disk-like members, 27 and 28, the member 27 having the lower half 105 reduced in diameter and the member 28 having a flange or apron, 29, at the bottom which projects into proximity to the reduced portion of the member 27.

After passing through the flanging devices 25 and 26, the work enters a mechanism similar to a wire straightener which straightens the flanges so that when the work leaves the machine its lines are straight and true. This mechanism, in the form 115 illustrated, consists of four rotary heads, 30, mounted to revolve about stationary axes, two of the heads being in position to engage with one of the flanges of the work after 120 passing through the flanging heads 25, and the other two being in a position to engage with the other flange of the work after it 125 passes through the flanging heads 26. Four other rotary heads, 31, arranged in the same relation to each other as that which the 130

heads 30 bear with respect to each other are so disposed that they may be moved transversely of the path of travel of the work, the arrangement being such that each flange 5 of the work passes between two of the heads 30 and two of the heads 31, so that by adjusting the heads 31, any desired effect on the flanges of the work may be produced.

It is desirable that the feeding heads of 10 each pair be adjusted from and toward each other, this being also true of the flanging heads, as the thickness of the material from which the laths are made varies and, in the case of the feeding heads, it is desirable that 15 the heads be pressed toward each other yieldingly so that they will always automatically adjust themselves and take a firm grip on the work. This may conveniently be accomplished by mounting one of the shafts of 20 each set of heads in such a way that it may be adjusted from and toward the other shaft. This is shown most completely, perhaps, in Fig. 5 of the drawing. One of the shafts for the set of flanging heads 25 is ar- 25 ranged in a stationary bearing, this shaft being indicated at 33, while the other shaft 34, extends eccentrically through a cylindrical bushing, 35, revolvably supported in an opening, 36, in the work-receiving bed. The 30 bushing 35 has an arm, 37, projecting radially from one side thereof and to this arm is secured the inner end of a bolt, 38, which passes through a stationary plate, 39, and has nuts, 40, arranged on opposite sides 35 of the plate. When the nuts 40 are screwed up against the plate 39, the supporting bushing for the shaft 34 is locked in place and the distance between the axes of the shafts 33 and 34 is fixed. If the metal of 40 which the laths are made varies in thickness, so as to require an adjustment of the flanging heads, this adjustment may be made by loosening the nuts 40 and swinging the bushing 35 around. The shaft for one of 45 the heads of the set 26 is supported in the same way as the shaft 34, the bolt, 41, corresponding to the bolt 38, being made longer because of the increased distance of the set of heads from the side of the machine. The 50 supporting shaft for one of the heads of each of the sets 20 and 21 is supported eccentrically in the bushing 35 as heretofore described, long bolts, 42, being employed instead of the bolt 38 and, instead of the nuts 55 on opposite sides of the stationary plate 39, there is no nut on the bolt on the inner side of the plate, while on the outer side there is a spring, 43, lying between the plate and a nut, 44, at the outer end of the bolt. 60 The parts are so proportioned that the springs, when free to do so, hold the feeding heads of each set together, so that no matter what the thickness of the material is, the flanges of the work will be firmly gripped by these heads.

All of the rotary heads heretofore described are driven in any suitable way from the main shaft so that the peripheral speed of all is the same and also the same as the speed at which the unexpanded channel is 70 fed into the expanding mechanism by the rolls 1 to 4.

Preferably there is beneath the work-receiving bed 9 a casing or housing, 45, closed at the top by this bed and forming an in- 75 closed chamber for housing the gears and for containing a bath of oil which will insure effective lubrication for the gears. The gearing is best shown in Fig. 6, wherein 46 represents a spiral gear carried by the driv- 80 ing shaft and meshing with a complementary gear, 47, on the shaft 33. The shaft 33 is geared to the shaft 34 and the shafts 51 and 52, 53 and 54, and 55 and 56 belong- 85 ing to the heads 25, 21 and 20, respectively, 90 are all geared together in a train which includes the shaft 34 and the shaft 33. In the same way, the shafts for the heads 30 and 31 are geared in a train starting from the shaft 33.

The heads 31 are carried upon slides, 57 and 58, which may be adjusted transversely by means of screw devices, 59, or otherwise. The shafts 60, 61, 62 and 63 on which the heads 30 are carried are driven by a direct 95 train of gearing, 64, beginning at the shaft 33 while the shafts 65, 66, 67 and 68 on which the heads 31 are carried are driven by a gear train the first two members of which are two large wheels, 70 and 71, carried by the 100 shafts 61 and 67, respectively. The slight movement of the slides 57 and 58 required to make the necessary adjustments of the straightening devices does not interfere with the driving connections of the shafts 65 to 105 68 as the gear wheel 71 rolls upon the gear wheel 70 and remains in operative relation thereto while the adjustments are being made. The shafts 65, 66, 68 and the necessary intermediate shafts are only long 110 115 enough to extend through the slides so as to support at their upper ends the rotary heads and at their lower ends the gear members, but the shaft 67 must project a considerable distance below the slide so as to carry the gear wheel 71 in a plane below the train beginning with the shaft 67. I have therefore provided a special bearing for the lower end of the shaft 67 as best 120 illustrated in Fig. 3. The lower end of the shaft 67 projects through a bearing in one end of an arm, 73, whose other end is secured to the under side of the slide 57. A shoe, 74, projects downwardly from the free end of the arm 73 into a groove or way, 125 75, in the top of a stationary part, 76, of the frame. With this arrangement, the arm 73 presses the shaft against lateral movement in one direction while the shoe and the guide or way coöperate to prevent lat- 130

eral movement in the direction at right angles. At the same time, the slide 57 may be moved back and forth to adjust the devices, the shoe 74 sliding along the guide or 5 way without leaving the same.

While I have illustrated and described with particularity only a single preferred form of my invention, I do not desire to be limited to the exact structural details thus 10 illustrated and described; but intend to cover all forms and arrangements which come within the terms employed in the definitions of my invention constituting the appended claims.

15 I claim:

1. In a machine of the character described, mechanism for bending the edges of a flat slotted strip laterally to shape it into a channel, mechanism for engaging the side 20 members of the channel to spread them apart and expand the channel, the block being so shaped that its longitudinal center line is curved and means for flanging the free edges of the side members of the channel.

2. In a machine of the character described, mechanism for bending the edges of a slotted strip laterally to give the strip the shape of a channel, a wedge shaped block lying in the vicinity of said mechanism with its narrow end directed toward said mechanism, and means for drawing the channel over 30 said block to expand the same and open the slits.

3. In a machine of the character described, mechanism for bending the side edges of a slotted strip laterally to give the strip the shape of a channel, a device in the vicinity of said mechanism containing curved diverging grooves each adapted to 40 receive one of the side members of the channel, and means for drawing the channel through said device to expand the same and open the slits.

4. In a machine of the character described, mechanism for bending a slotted strip into a channel, mechanism for expanding the channel, mechanism for flanging the free edges of the side members of the channel, mechanism acting on the side members 50 of the expanded channel to make the channel straight, and means for driving said mechanisms in unison with each other so as to cause them to act in succession on a piece of work passing through the machine.

5. In a machine of the character described, mechanism for expanding a sheet metal channel having the bottom member slotted, mechanism for flanging the free edges of the side members of the channel, 60 and means for driving said mechanisms in unison with each other so as to cause them to act in succession on a piece of work passing through the machine.

6. In a machine of the character described, means for expanding a sheet metal

channel having the bottom member slotted, a jaw adjustable transversely of the path of movement of the channel in the machine and being of a size to receive one of the side members of the channel, and mechanism for 70 drawing a channel through the expanding means and through said jaw.

7. In a machine of the character described, mechanism for expanding a sheet metal channel having the bottom member slotted, mechanism for flanging the free edges of the side members of the channel, mechanism for acting on the flanged side members of the expanded channel to make 75 the channel straight, and means for driving said mechanisms in unison with each other so as to cause them to act in succession on a piece of work passing through the machine.

8. In a machine of the character described, an expanding member comprising 85 a wedge-shaped block having its diverging sides curved in the same general direction, and means for drawing a channel-shaped strip to be expanded over said block.

9. In a machine of the character described, mechanism acting upon a strip of sheet metal having a slotted central panel extending throughout the length of the same to form it into a channel having the slotted portion for the bottom, and mechanisms for 90 successively expanding the channel and flanging the side members thereof.

10. In a machine of the character described, a series of sets of horizontal rolls for transforming a strip of sheet metal having a slotted panel extending through the center thereof into a channel having the bottom formed of said panel, cooperating feed heads rotatable about vertical axes, and an expanding device arranged between said 100 rolls and said feeding heads and provided with diverging grooves curved in the same general direction for receiving the side members of the channel to expand the channel as it is drawn forward by said feeding heads.

11. In a machine of the character described, a series of sets of rolls for transforming a strip of sheet metal having a slotted panel extending through the center thereof into a channel having the bottom formed of said panel, an expander for receiving the channels from the rolls and stretching it so as to open the slits in the bottom, means for drawing the channel through said expander, and means for flanging the side members of the expanded channel.

12. In a machine of the character described, an expanding member in the form of a wedge-shaped block having at one side a straight edge and terminating at one end of the block in a portion curved in the direction of the opposite side, and having at the latter side an edge straight at the last mentioned end and curved away from the 125

- opposite side in the vicinity of the other end of the block.
13. In a machine of the character described, mechanism for transforming a metal strip having a slotted central panel into a channel having the bottom formed out of the said panel in an expanded condition, and a series of rotary heads arranged in staggered relation to each other on opposite sides of each of the flanges or sides of the channel leaving said mechanism for straightening the channel.
14. In a machine of the character described, means for acting on the bottom of a channel-shaped strip having a slotted bottom so as to deflect at least a portion thereof out of its normal plane to start the opening of the slits slightly and cause the strands to be deflected in the desired direction without producing any considerable expansion of the strip, and means for thereafter acting on the side members of the strip to expand the slotted bottom.
15. In a machine of the character described, means for progressively deflecting the slotted bottom of a channel-shaped strip throughout at least a portion of its width to start the opening of the slits and direct the strands in the direction in which they are to be laid without producing any considerable expansion of the strip, and means for progressively acting on the side members of the strip in order to expand the same progressively after the preliminary opening of the slits.
16. In a machine of the character described, means for deflecting at least a portion of a slotted sheet out of its normal plane to start the opening of the slits and determine the direction in which the strands are to lie without producing any considerable expansion of the strip, and means for thereafter exerting a pull in opposite directions in approximately the normal plane of the sheet to expand the same and fully open the slits.
17. In a machine of the character described, means for progressively deflecting a slotted sheet out of its normal plane for at least a portion of its width in order to start the opening of the slits and determine the direction in which the strands are to be laid and without producing any considerable expansion of the sheet, and means for acting upon the sheet progressively as the slits are opened and exerting a pull in opposite directions in approximately the normal plane of the sheet to expand the same and completely open the slits.
18. In a machine of the character described, means for deflecting a slotted sheet out of its normal plane for at least a portion of its width so as to start the opening of the slits and determine the direction in which the strands shall be laid while only incidentally producing an expanding effect on the sheet, and means for exerting a pull in opposite directions on the sheet in approximately the normal plane of the sheet for the purpose of producing substantially the total expansion thereof after the opening of the slits has been started.
19. In a machine of the character described, means for feeding a strip in the direction of its length, means for progressively deflecting at least portions of the strip out of its normal plane as the feeding proceeds, so as to start the opening of the slits and determine the direction in which the strands shall be laid while only incidentally producing an expanding effect on the strip; and means for applying a transverse pull in opposite directions in approximately the normal plane of the sheet, after the opening of the slits has been started, for the purpose of producing substantially the major portion of the expansion of the strip.
20. In a machine of the character described, means for feeding a slotted strip in the direction of its length, means acting on the strip as a step preliminary to the expansion thereof to bow it out of its normal plane so as to start the opening of the slits and determine the direction in which the strands shall be laid while only incidentally producing an expanding effect; and means for applying a transverse pull in opposite directions in approximately the normal plane of the strip to effect substantially the entire amount of the expansion to which the strip is to be subjected.
21. In a machine of the character described, means for feeding a slotted strip in the direction of its length, means acting on the strip along a longitudinal line between the sides as a step preliminary to the expansion thereof to pass the strip laterally and cause the portions on opposite sides of said line to be inclined toward each other so as to start the opening of the slits and determine the direction in which the strands shall be laid while only incidentally producing a slight expansion of the strip, and means for applying to the strip a transverse pull in opposite directions in approximately the normal plane of the slotted strip to bring about substantially the whole of the expansion to which the strip is to be subjected.
22. In a machine of the character described, means for bending a slotted sheet transversely out of its normal plane to start the opening of the slits and determine the direction in which the strands shall be laid while only incidentally producing a slight expansion of the sheet, and means for exerting pulls in opposite directions on the sheet in approximately the normal plane of the sheet for the purpose of producing substantially the entire amount of expansion to which the sheet is to be subjected.
23. In a machine of the character de-

scribed, means for bending a sheet transversely out of its normal plane along a line parallel with the slits so as to start the opening of the slits and determine the direction 5 in which the strands shall be laid while producing incidentally only a slight expansion of the sheet, and means for thereafter exerting pulls in opposite directions on the sheet to effect substantially the entire 10 amount of expansion to which the sheet is to be subjected.

24. In a machine of the character described, means for applying at the sides of a slitted sheet pulls in opposite directions 15 and approximately in the normal plane of the sheet to open the slits and expand the same, and additional means acting on the sheet as a step preliminary to the expansion to start the opening of the slits and determine 20 the direction in which the strands shall be laid while producing an incidental slight expansion of the sheet.

25. In a machine for expanding a channel-shaped slit having a slitted bottom, a block increasing gradually from one end to the other from a width equal to the unexpanded channel to the width of the expanded channel, the top of the block being recessed, means for drawing a channel to be 30 expanded over said block, and means for depressing the slitted portion of the channel into the recess in the top of the block at the narrow end of the block.

26. In a machine for expanding a sheet 35 metal channel having a slitted bottom, a block increasing in width from a width equal to that of the unexpanded channel to that of the expanded channel, means for drawing the channel over the block, and means associated with the block for determining the angle of inclination of the strands to the normal plane of the bottom member of the channel.

27. In a machine for expanding a sheet 45 metal channel having a bottom slitted so as to expand into a diamond mesh when the channel is expanded, a block increasing gradually in width from end to end, means for drawing the channel over the block with its flanges in engagement with the sides 50 thereof, and additional means for positively determining the direction in which the strands will be inclined to the normal plane of the bottom of a channel when the channel is expanded.

28. In a machine for expanding a sheet 60 metal channel having a bottom slitted so as to expand into a diamond mesh when the channel is expanded, a block having at one end a width equal to the width of the unexpanded channel and increasing gradually in width to that of the expanded channel, the top of the block being cut away along the middle to provide a recess extending 65 from the narrow end toward the wider end,

means for drawing a channel to be expanded over said block with its flanges engaging the sides of the block, and means for deflecting the slitted bottom of the channel into said recess. 70

29. In a machine for expanding a sheet metal channel having a bottom slitted so as to expand into a diamond mesh when the channel is expanded, a block having at one end a width equal to the width of the unexpanded channel and increasing gradually in width to that of the expanded channel, the top of the block being cut away along the middle to provide a recess extending from the narrow end toward the wider end, 75 means for drawing a channel to be expanded over said block with its flanges engaging the sides of the block, and a cam-shaped shoe arranged above said block and having a portion extending down into said recess 80 in proximity to the narrow end of the block. 85

30. In a machine for expanding a sheet metal channel having a slitted bottom, a block of the same width as the channel at one end and increasing gradually in width 90 toward the other end, the top of the block being cut away except at the edges so as to provide a recess bound at the sides by two upwardly-projecting ledges, means for drawing a channel to be expanded over said block, and means for pressing the slitted bottom into said recess at the narrower end 95 of the block.

31. In a machine for expanding a sheet metal channel having a slitted bottom, a block of the same width as the channel at one end and increasing gradually in width toward the other end, the top of the block being cut away except at the edges so as to provide a recess bound at the sides by two 100 upwardly-projecting ledges, means for drawing a channel to be expanded over said block, and a shoe supported above the block 105 in proximity to one side thereof, said shoe projecting down into said recess in proximity to the latter ledge and having its under face inclined downwardly as said ledge is approached, and the advance end of the shoe being inclined upwardly at the under side to permit the entrance of a channel to be expanded. 110

32. In a machine for expanding a sheet metal channel having a slitted bottom, a block increasing gradually in width from a width equal to that of the unexpanded channel to that of the expanded channel, one of the sides of the block being substantially straight and terminating at the wide end of the block in an inwardly directed curve, and means for drawing a channel to be expanded over said block. 120

33. In a machine of the character described, mechanism for bending the edges of a flat slitted strip laterally to shape it into a channel, a wedge block of a width at one end 130

to enter said channel and having a width at the opposite end corresponding to the width of the expanded product, and means for drawing the channel over said block, 5 said block being bent as a whole so that the path of travel of the channel when leaving the block is at an angle to the path of travel at the point where it first engages with the block.

10 34. In a machine of the character described, mechanism for bending the edges of

a slotted strip laterally to give the strip the shape of a channel, and means for progressively expanding the slotted bottom of the channel and at the same time swinging the 15 expanded portion of the channel so as to bring its center line at an angle to the longitudinal center line of the unexpanded part of the channel.

In testimony whereof, I sign this specification.

FRED C. AREY.
